CAN STRIP REMOVER

Robert W. Reeves, Allendale, S. C.

Application May 12, 1953, Serial No. 354,485

1 Claim. (Cl. 220—52)

This invention relates to new and useful improvements in can opening devices and more particularly to an opener for cans having tops retained on the can bodies by removable strips.

The primary object of the present invention is to provide a can strip remover that will ride about the periphery of a can and which includes a key that is rotated to wind a can strip thereabout, the key being retracted to release the wound strip therefrom.

Another important object of the present invention is to provide a can strip remover including a guide having an opening into which the slotted end of a key may be moved or retracted so that a strip wound about the slotted end of the key will be removed therefrom as the slotted end is retracted from the opening.

A further object of the present invention is to provide a can strip removed of the aforementioned character including a leaf spring engageable with the key to selectively retain the slotted end of the key in or out of the opening in the guide.

A still further aim of the present invention is to provide a can strip remover that is simple and practical in construction, strong and reliable in use, small and compact in construction, neat and attractive in appearance, efficient and reliable in use, inexpensive to manufacture, and otherwise well adapted for the purposes for which the same is intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top plan view of the invention in use;

Figure 2 is an enlarged fragmentary vertical sectional view taken substantially on the plane of section line 2—2 of Figure 1;

Figure 3 is a horizontal sectional view taken substantially on the plane of section line 3—3 of Figure 2;

Figure 4 is a perspective view of the present invention; and

Figure 5 is a view similar to Figure 2 but showing the invention removed from the can and the key retracted to release the strip.

Referring now to the drawings in detail, wherein for the purpose of illustration, there is disclosed a preferred embodiment of the present invention, the numeral 10 represents a guide member having a substantially rectangular lower portion 12 that is provided with an opening 14 and upper and lower horizontal parts 16 and 18.

Guide member 10 also includes a substantially L-shaped member comprising a vertical flange 20 and a horizontal flange 22. The horizontal flange 22 overlies the lower portion 12 and is provided with an aperture 24 that registers with registering apertures 26 and 28 in the parts 16 and 18.

2

The shank portion 30 of a key 32 is slidably and rotatably positioned in the apertures 24, 26 and 28. The lower bifurcated or slotted end 34 of shank portion 30 extends through the opening 14 and into aperture 28 when the key 32 is in use and may be retracted from aperture 28 and opening 14.

One end of a leaf spring 36 is fixed by welding or the like to flange 20 under flange 22. The spring 36 yieldingly engages the shank portion 30 to maintain the key 32 retracted and will slip over a shoulder lug 38 fixed to shank portion 30 when said key is returned to operative position in opening 14. A second shoulder lug 40 is fixed on shank portion 30 above flange 22 and will abut flange 22 to limit downward sliding movement of the key.

A prying element 42 is fixed to or integrally formed with one end of guide member 12. This prying element is provided with a beveled edge 43 that is used for bending the free end portion E of a can tear strip S outwardly so that the free end portion of the strip may be engaged in the slot of end 34.

In practical use of the present invention, the end portion E of strip S is engaged in the slot of the key end 34 and member 10 is placed against the outer periphery of the can C. The key 32 is lowered to its operative position with spring 36 engaged over shoulder element 38. Then the key is rotated to wind the strip S thereon as the guide lugs 44 and 46 on parts 16 and 18 of member 10 travel about the periphery of the can. After the strip S is completely wound on key end 34, spring 36 is depressed and the key raised, as shown in Figure 5, and the guide member 10 is tilted so that the strip will engage part 16 to be released from end 34 and the strip S will pass from opening 14.

What is claimed as new is as follows:

A can strip remover comprising a guide member including a substantially rectangular lower portion having an opening and an L-shaped upper portion, said upper portion being provided with a horizontal flange overlying said lower portion, said horizontal flange having an aperture, said lower portion having an upper part and a lower part each provided with an aperture in registry with the aperture in said horizontal flange, a key including a shank portion slidably and rotatably engaged in said apertures, the shank portion having a bifurcated lower end disposed in said opening to engage one end of a can strip, and said key being raised to retract the bifurcated end from the opening whereupon a strip wound about said bifurcated end will engage the upper part to be released from the key, means carried by said member restricting sliding movement of said key and selectively retaining the bifurcated end in and out of the opening, wherein said means comprises a leaf spring fixed at one end to the vertical flange of said upper portion, and a shoulder element fixed to said shank portion over said bifurcated end and engaged under the spring when the bifurcated end is disposed in said opening.
